UNITED STATES PATENT OFFICE.

FANNIE B. S. BEARDSLEY, OF TOPEKA, KANSAS.

DESIGN FOR A BUTTON.

SPECIFICATION forming part of Design No. 26,012, dated September 15, 1896.

Application filed June 25, 1896. Serial No. 596,950. Term of patent 3¹ years.

To all whom it may concern:

Be it known that I, FANNIE B. S. BEARDSLEY, a citizen of the United States, and a resident of Topeka, county of Shawnee, and State of Kansas, have invented and produced a new and original Design for Buttons, of which the following is a specification, reference being had to the accompanying drawings, forming a part thereof, in which similar letters of reference indicate corresponding parts.

Figure 1 is a side elevation of my new and original design for buttons, and Fig. 2 is a plan view thereof.

The leading feature of my design is a representation of a "buckeye," (designated in the drawings by the letter A.) This forms the head of the button, and it has the irregular outlines and contour as well as the natural

color of a thoroughly ripe buckeye. This said head is mounted upon a cylindrical shank B, which has a circular plate b upon the bottom thereof, which is elliptical in side elevation.

What I claim is--

The design for a button herein shown and described, the same comprising the head A of irregular contour and the shank B having the plate b forming part thereof, as set forth.

In testimony that I claim the foregoing as my invention I have signed my name, in presence of two witnesses, this 22d day of June, 1896.

FANNIE B. S. BEARDSLEY.
Witnesses:

HENRY C. FELLOWS,
Mrs. JAMES A. STAPLES.
